UNITED STATES PATENT OFFICE.

STILLMAN W. ROBINSON, OF COLUMBUS, OHIO, ASSIGNOR TO THE WIRE GRIP FASTENING COMPANY, OF BOSTON, MASSACHUSETTS.

NAILING-MACHINE.

SPECIFICATION forming part of Letters Patent No. 591,658, dated October 12, 1897.

Application filed March 25, 1897. Serial No. 629,169. (No model.)

To all whom it may concern:

Be it known that I, STILLMAN W. ROBINSON, of Columbus, county of Franklin, State of Ohio, have invented an Improvement in 5 Nailing-Machines, of which the following description, in connection with the accompanying drawings, is a specification, like letters and figures on the drawings representing like parts.

10 This invention has for its object the production of a novel machine for making nails or fastenings from a nail-strip and driving them as made.

One part of my invention in nailings-machines consists of a plate provided with a pointing-quill having a nail-strip passage and a driver-passage, combined with a pivoted swing-plate provided with a cutting or pointing tool and a suitable means to actuate 15 said swing-plate, substantially as described; also, of a plate provided with a pointing-quill having a nail-strip passage and a driver-passage, combined with a pivoted swing-plate provided with a cutting or pointing tool and having a cam-slot, and a carrier-plate having a stud entering said cam-slot, substantially as described; also, of a plate provided with 20 a pointing-quill having a nail-strip passage and a driver-passage, combined with a pivoted swing-plate provided with a cutting or pointing tool and having a cam-slot, and a carrier-plate having a stud entering said cam-slot, substantially as described; also, of a plate provided with 25 a pointing-quill having a nail-strip passage and a driver-passage, combined with a pivoted swing-plate provided with a cutting or pointing tool and having a cam-slot, and a carrier-plate having a stud entering said cam-slot, having two shoulders between its ends to impart to said carrier-block intermittently 30 reciprocating motion, substantially as will be described.

The particular features in which the invention consists will be hereinafter fully described, and indicated in the claims at the 40 end of this specification.

Figure 1, in front elevation, shows a sufficient portion of a nailing-machine with my improvements added to enable my invention to be understood. Fig. 2 shows part of the 45 nail-strip-feeding mechanism; Fig. 3, the adjusting device for determining the length of strip to be fed to thus make a nail of the desired length. Fig. 4 shows a right-hand side elevation of the machine represented in Fig. 50 1. Fig. 4^a is a face view of the carrier-plate and its grooved block. Fig. 4^b is a top or

plan view thereof showing the eccentric for adjusting the position of said block. Fig. 4^c shows detached the pin which constitutes a pivot for said block. Fig. 4^d is a face view 55 of the auxiliary cutting-block. Fig. 4^e is a plan view of the short link or block c⁶. Fig. 5 shows the top plate detached. Fig. 6 shows the nose-plate detached and in top view. Fig. 7 shows the carrier-plate mounted on the nose- 60 plate. Fig. 8 shows the same parts with the swing-plate in its other extreme position. Fig. 9 shows the swing-plate mounted on the carrier-plate, the swing-plate occupying its normal position, with the pointing-quill in its 65 position to be actuated to nick or chip the strip in the formation of the point. Fig. 10 shows the swing-plate in edge view, with its attached presser-block. Fig. 11 shows said presser-block detached in two views. Fig. 70 12 shows end views and side elevation of the pointing-quill. Fig. 12^a shows a nail-strip nicked as it will be in practice before it is cut off in the formation of a nail. Fig. 13, in top view, shows a modified form of top plate. Fig. 75 14 shows a modified form of nose-plate. Fig. 15 shows the carrier-plate mounted on the nose-plate. Figs. 16 and 17 show a modified form of swing-plate mounted above the carrier-plate and in two different views. Fig. 80 18 shows an edge view of the front portion of the swing-plate, with its connected presser-block; and Figs. 19 and 20 show two different views of the presser-block. Figs. 21, 22, and 23 show different views of the pointing- 85 quill.

The framework A of the main head, in practice mounted on a suitable column A', has bearings for the main shaft A², provided with an eccentric A³, a ratchet-wheel A⁴, and a toe- 90 cam A⁵ to act on a block A⁶, secured to and adapted to lift the driver-bar A⁷, provided with a driver A⁸. This driver-bar as soon as the toe of the said cam lifts and passes the block A⁶ is quickly thrown down by a 95 spring B, one end of which is connected with a stud B' of an arm B⁹, fixed on a rod B², the opposite or free end of the spring acting on a stud B³, extended from an arm B⁴, loose on said rod B², the end of said arm acting on a link 100 or upright B⁵, seated on or jointed to the driver-bar.

The eccentric A³ is embraced by an eccentric-strap at the upper end of the lever C, having a hub C', which embraces a pin C², mounted in arms of a link C³, pivotally mounted on a 5 horizontal pin C⁴, fixed in suitable ears projecting from the head A.

The lower end of the lever C has a pin or stud C⁵, on which is fitted loosely the hub c (see Fig. 4^e) at one end of a short link or 10 block C⁶, the opposite end of said link having a second hub c' bored at right angles to the bore in the hub c, said hub c' embracing and sliding freely on a stud c², rising from an ear c³ of a swing-plate C⁷ to be described.

15 The link C⁶ and the pins or studs with which it is connected form a double sliding joint, and as the said lever is vibrated on its pivot c² in the link c³ the swing-plate is moved in a plane at right angles to the main shaft 20 A² by an easy link motion.

25 The nail-strip a, wound in the form of a roll or coil, is sustained by a suitable spool a', mounted on the end of an adjustable arm a², secured to the stud B². The end of the nail-strip is led through a suitable guide a³, and thence between the face of a feed-wheel a⁴ and the side of a wheel a⁵. (See Fig. 1.)

30 The pressure of the wheel a⁵ toward the feed-wheel to gage the force with which the nail-strip may be pinched will be controlled by a spring a¹⁴, acted upon by a screw a¹⁵. The feed-wheel is mounted loosely on the stud C⁴ and has a sleeve-hub provided with a wheel a⁶, having teeth which are adapted to 35 be engaged by a pawl a⁷, mounted loosely on the pin or stud C², the latter pin or stud in its movements with the link C³ causing said pawl to be moved to turn the feed-wheel. The extent of the movement of the feed-wheel 40 by said pawl may be altered as desired by turning about the stud C⁴ the feed-regulating lever b, it having a pawl-controlling shield b', on which rides one edge 2 of the pawl, and by 45 adjusting the position of this shield b' about said wheel a⁶ the pawl in its movement may engage the teeth of said wheel sooner or later and so move the feed-wheel for a greater or less distance, according to the length of nail desired for the work being nailed. The lever 50 has a spring-pressed pin b⁸, which, by its engagement with the teeth of a sector b⁹, locks the said lever in any position in which it may be left.

55 Extended from the frame is a screw b⁶, (see Fig. 2,) on which is an adjustable stop b⁷, and a second one b⁸, which may be struck by a projection 3 of the lever b, the position of the said stop b⁷ on said screw determining the length of the shortest nail to be used, while 60 the stop b⁸ is to be adjusted for the longest nail. After leaving the feed-wheel the nail-strip, of whatever cross-section, is led into the orifice d of the pointing-quill D, it having also a driver-passage d', the lower end of 65 said quill below the top plate D', on which it is secured, being slabbed off, as shown in Fig. 12, to leave a secant surface in which may

move the cutting end of the cutting or pointing tool D², the secant cut exposing the strip-passage. The top plate D' is securely attached to the end of the main head of the machine by suitable bolts d² and g³ and extended downwardly from it are two steel studs d³ d⁴.

70 The stud d³ constitutes a fulcrum for the swing-plate C⁷, (shown best in Figs. 8, 9, and 10,) it carrying the cutting or pointing tool D², said tool being held between a shoulder of the swing-plate and a clamping-block d⁵, pivoted to the swing-plate at d⁶, said block 80 being acted upon by a suitable adjusting device d⁷, shown as a screw. The cutting-tool is held up to its work by a screw d⁸, acting against its rear end. This swing-plate has attached to it by a suitable screw d⁹ at the 85 front side of the pointing-tool a presser-block d¹⁰, which acts against one edge of the nail-strip to hold it properly in the strip-groove of the said pointing-quill preparatory and while the cutting-tool is acting to cut away a 90 portion of the strip and leave a notch preparatory to the formation of a nail-point. This swing-plate has a cam-slot E. Directly beneath this swing-plate I place a carrier-plate F, it turning freely about the stud d⁴, 95 depending from the top plate.

The carrier-plate has extended above it a steel stud F', shown as rectangular in cross-section, it entering the cam-slot E of the swing-plate, the said carrier-plate deriving 100 its motion from the cam of the swing-plate. When the swing-plate is in its position (see Fig. 9) to permit the nail-strip to be fed into the pointing-quill, the stud F' stands in the right-hand end of the cam-slot. Now when 105 the swing-plate is moved to cause the pointing-tool to cut, the shoulder e of the cam-slot acts against the said stud and swings the carrier-plate with it in the same direction, but for a limited distance.

110 When the reverse motion of the swing-plate takes place, it starts and has a limited amount of movement in the left-hand end of the cam-slot, and then the second shoulder e' of the cam-slot meets the said stud, and thereafter the swing-plate moves the cam-plate with it for a limited distance and then drops it while the swing-plate returns to its normal or starting point. This carrier-plate is provided with a grooved block e², (see Figs. 120 8 and 4^a,) it having a driver-passage e³ and at its upper end a lip e⁴, which overlaps the upper end e⁵ of an auxiliary cutting-block e⁶ mounted on the nose-plate G.

125 The grooved block e² is in Fig. 4^a shown as attached by a suitable screw e⁷ to an arm e⁸, pivoted to the carrier-block at one end by a suitable pin e⁹, and to provide for altering the effective length of this arm and consequently determine to a nicety the position of the driver-groove therein with relation to the driver-groove in the pointing-quill above it I have provided between the said pin and the 130 said arm an eccentric f, (see Fig. 4^b,) which

may be turned when desired to effect any nice adjustments of the block e^2 . This eccentric in this embodiment of my invention is shown as clamped in a split end of the arm e^3 by a clamp-screw f' . The two studs d^3 and d^4 also enter holes f^2 and f^3 in the nose-plate G , said plate being provided at its under side with any usual or suitable nose-tube g .

- 10 At one side of the nose-plate is an upright lug or ear g' , provided with two threaded holes g^2 for the reception of two screws g^3 , which are extended through a suitable flange g^4 on the main head-frame, (see Fig. 1,) said screws 15 also passing through the top plate of the working head and serving as an additional means to not only connect the top plate at the main head, but also the said nose-plate to the top plate.
- 20 The auxiliary cutting-block e^6 has a driver-
passage 4, and one edge of the said block is
cut away to leave a shearing edge 5, against
which the strip is carried, it having previ-
ously had cut from it by the tool D^2 a por-
25 tion at the edge to aid in forming a point.

Fig. 12^a shows the nail-strip as it will appear when most of the cuts are made, and said strip has at its lower end a point 6, and above said end it has a second like notch 7, which, as before said, aids in forming the point of the next nail. Now in this condition the carrier-plate will be swung in the direction to carry the nail toward the driver-
passage of the auxiliary cutting-block, and in 30 this movement the nail-strip will be cut off in the line x^2 , and at the same time or im-
mediately after the portion of the strip to make the nail next to be driven will have cut from its edge between its own point 6 and 35 the previously formed point above it 7 a space 8 to thus form the body of the nail and leave a head 9 for the nail, the severing of the strip transversely completing the point above it for the succeeding nail. The nail 40 thus cut off from the strip is by a further movement of the carrier-block brought into such position with relation to the driver-
groove 4 in the auxiliary cutting-block e^6 as to enable the driver to meet the upper end 45 or head of the nail or fastening, drive it out through the nose-tube g , the head of the nail in this further lateral motion of the carrier-
block and its arm resting on and traveling over the upper end of the said auxiliary cut-
ting-block.

By providing the auxiliary cutting-block with a shearing edge, as described, which may be of any desired curve or angle, it is possible to so cut into the edge of the thin metallic strip used as to gradually remove therefrom a portion, thus materially lessening the force required for removing the chip.

In order to hold the arm e^3 up firmly in place during the time that it is cutting and moving 60 the nail, as stated, I have provided the nose with a bearing-plate h , it being held in place by a suitable screw h' .

Sheet 4: Figs. 13 to 23 show a modified form of my invention. In said figures the top plate D' and the swing-plate are substantially the same as hereinbefore described, but the shape of the nose-plate G^{20} and of the carrier-plate F^{20} are somewhat modified. For instance, the nose-plate presents the upper end of the nose-tube with only a hole g^{20} for 70 both the nail and the driver and the carrier-plate has a steel carrier-tube f^{20} , held supported by a screw f^{22} , said tube having a hole f^{21} , in which is fed the end of the wire, a round or rectangular corrugated wire, and 75 then by the movement of the carrier through the swing-plate, as described, the tube coöperating with the lower end of the pointing-quill D^{20} cuts off the wire for the nail and puts the tube f^{21} , containing the nail, in line 80 with the descending driver, letting the driver act on and drive the nail from the carrier-tube and nose-plate. In said Sheet 4 d^{10x} represents the pressure-block.

Having described my invention, what I 90 claim, and desire to secure by Letters Patent, is—

1. In a nailing-machine, a pointing-quill having a nail-strip passage and a driver-passage, combined with a pivoted swing-plate 95 provided with a cutting-tool, and a suitable means to actuate said swing-plate, substantially as described.

2. In a nailing-machine, a pointing-quill having a nail-strip passage and a driver-passage, combined with a pivoted swing-plate 100 provided with a cutting-tool, and a pressing-block to act on the nail-strip, substantially as described.

3. In a nailing-machine, a pointing-quill 105 having a nail-strip passage and a driver-passage, combined with a pivoted swing-plate provided with a cutting-tool, and means to clamp and adjust the said cutting-tool on or with relation to said plate, substantially as 110 described.

4. In a nailing-machine, a fixed pointing-quill having a nail-strip passage and a driver-passage, combined with a pivoted swing-plate provided with a cutting-tool, and having a 115 cam-slot and a carrier-plate having a stud entering said cam-slot, substantially as described.

5. In a nailing-machine, a pointing-quill having a nail-strip passage and a driver-passage, a pivoted swing-plate provided with a cutting-tool, and having a cam-slot provided with two shoulders between its ends, combined with a carrier-plate having a stud entering said cam-slot, whereby said swing-plate is enabled to impart intermitting reciprocating motion to said carrier-plate, substantially as described.

6. The pointing-quill having two slots, one for the driver and the other for the nail-strip, 120 the lower end of the quill being slabbed off to leave a secant face in which is exposed the nail-strip groove, substantially as described.

7. A pointing quill or block having a nail-

- strip passage and a driver-passage and means for holding it, a driver, a swing-plate provided with a cutting-tool and having a cam-slot, a carrier-plate located below said swing-plate and having a nail-carrying block and a stud, combined with a nose-plate having a nose-tube, and with means to actuate said swing-plate and said driver, substantially as described.
10. 8. A pointing-quill having a nail-strip passage and a driver-passage, a driver, a swing-plate provided with a cutting-tool and having a cam-slot, a carrier-plate located below said swing-plate and having a pivoted arm pro- 5
15. vided with a nail-carrying block and a stud, combined with a nose-plate having a nose-tube, an auxiliary cutting-block, said nail-carrying block and auxiliary cutting-block being shaped substantially as described to 20
20. form a head on the nail to be made as set forth.
9. In a nailing-machine, a pointing-quill having a nail-strip passage, a swing-plate having a pointing-tool coöperating with said pointing-quill to cut from the strip a chip to 25
25. aid in forming the point of a nail, a carrying-plate provided with a nail-carrying block having a combined nail and driver passage, and provided at its upper end with a lip, a nose-plate, an auxiliary cutting-block with 30
30. which said nail-carrying block coöperates, said auxiliary cutting-block having a shearing edge, and means to actuate said carrier-block and said nail-carrying block to remove 35
35. from the nail-strip a portion of its edge above the previously-formed point and leave at the upper end of the portion so last cut away a head, substantially as described.
10. In a machine of the class described, a carrying-plate, an arm provided with a nail- 40
40. carrying block, a pin connecting said arm and block and an eccentric located at said pin to, by its adjustment, determine the exact position of the said nail-carrying block on the said carrying-plate, substantially as described.
45. 11. A nose-plate provided with an auxiliary cutting-block, and a carrier-plate provided with an arm having a nail-carrying block, means to actuate said carrier-plate, combined 50
50. with a bearing-plate to act on and hold the said arm and its nail-carrying block up firmly to the auxiliary cutting-block, substantially as described.
12. In a nailing-machine, a pointing-quill, 55
55. means to hold it, a swing-plate provided with a cutting-tool, a lever, a pivoted link carrying the fulcrum for said lever, combined with a sliding block loosely connecting one end of said lever with said swing-plate, substan- 60
60. tially as described.
13. In a nailing-machine the following instrumentalities, viz: a pointing quill or block having a wire-passage and a driver-passage and means for holding it, a driver, a swing-plate containing a pointing-tool and a cam-slot, a carrier-plate having an attached nail-carrier piece and a stud working in said cam-slot, substantially as described. 65
14. In a nailing-machine, the following instrumentalities, viz: a feeding mechanism to 70
70. feed a nail-strip intermittently; a pointing-quill to receive the end of the said nail-strip; a pointing-tool coöperating with said pointing-quill; means to move said pointing-tool to cut into and remove a portion of said strip 75
75. from one edge thereof to leave a notch at a distance from the end of the strip equal to the length desired for the nail next to be cut from the strip, an auxiliary cutting-block having a driver-passage and a shearing edge; a carrier-plate located below the pointing-tool and provided with a driver-passage and having a lip to overlap the upper end of said auxiliary cutting-block, and means to move said carrier-plate, whereby the notched edge of the 80
80. strip is further cut away from the top of said notch upwardly for the length desired for the shank of said nail being made below its laterally-extended head, and the said strip is at the same time severed transversely above the 85
85. head of the nail, leaving it in condition to be driven, substantially as described.
15. In a nailing-machine, the feeding mechanism to feed a nail-strip, a plate provided with a pointing-quill having a nail-strip pas- 90
90. sage and a driver-passage, combined with a pivoted swing-plate provided with a cutting-tool, and suitable means to actuate said swing-plate, substantially as described. 95
16. In a nailing-machine, feeding mechan- 100
100. ism as described to feed a nail-strip, combined with a lever operated by an eccentric on the main shaft, and a pivoted link carrying the fulcrum of said lever, substantially as de- 105
105. scribed.
17. In a nailing-machine, feeding mechanism consisting of a feed-roll, a pressure-roll and a ratchet-roll, a lever, a link, and a click mounted upon the pivot of the said lever and link, as described, combined with a lever 110
110. working between stops for controlling the length of the nail, substantially as described.
- In testimony whereof I have signed my name to this specification in the presence of two subscribing witnesses.
- STILLMAN W. ROBINSON.
